BENJAMIN W. BROUWER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT REPLENISHING MECHANISM FOR LOOMS

Application filed December 19, 1930. Serial No. 503,510.

This invention relates to improvements in weft replenishing looms and it is the general object of the invention to simplify mechanisms of this type particularly usable on multicolor looms to the end that several of the cooperating parts may be kept in proper relative position.

In the usual multicolor weft replenishing loom there is provided a storage magazine under which is located the weft detector. The magazine has as an integral part thereof a so-called color slide which has angular and longitudinal movements. The movements of this slide are determined in part by the weft detector through a controller, an actuating lever which is mounted on a reciprocating rod head, and a connector from the lever to the color slide. As heretofore constructed the guide for the rod head has been fixed to the loom frame so as to be immovable under ordinary conditions and not capable of adjustments with the feeler. Due to one reason or another it is occasionally desirable to adjust the location of the feeler relatively to the length of the shuttle and in the past this has necessitated further adjustments to render effective the controller for the actuator lever. This is particularly true when a side slip feeler is employed. It is an important object of my present invention to provide a single mounting for the actuating lever, the controller therefor, and the weft detector, to the end that these parts when once adjusted in proper relation can always be so maintained even though the detector be moved to different positions along the length of the lay.

It is desirable that as much of the automatic weft replenishing features as possible be assembled as a unit at one place before application to the loom and it is a further object of my invention to provide the magazine with a holder for the previously mentioned common support so that the magazine and the detector together with its controller and lever may be assembled as a unit. This operation is facilitated by reason of the fact that the link which connects the actuating lever with the color slide is free to move in

a plane parallel to the direction of adjustment of the detector along the lay.

A still further object is to provide means to move the guide for the actuator lever mounting in a direction toward and from the lay for the purpose of aligning the guide with the mounting and thus prevent wear.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a weft replenishing magazine of the multicolor type having my invention applied thereto,

Fig. 2 is a horizontal section taken on line 2—2 of Fig. 1,

Fig. 3 is a vertical section on line 3—3 of Fig. 2, and

Fig. 4 is a vertical section on line 4—4 of Fig. 3.

Referring particularly to Fig. 1, I have shown a loom frame 10 having a supporting platform 11 on which is mounted the foot 12 of a replenishing mechanism designated generally at M. The latter has mounted therein for longitudinal movement in a direction transverse of the lay a rod or shaft 13 carrying fingers 14 one of which is shown in Fig. 1 and having also a rod 15 supported rigidly with respect thereto. The sliding shaft 13 together with the fingers and rod 15 constitute the previously referred to color slide and is under control of a pattern mechanism as regards its longitudinal position transversely of the lay. Angular movement of the color slide is accomplished through a link 16 to the upper end of which is adjustably threaded a head 17 having sliding engagement with the rod 15.

The lower end of the link 16 is pivotally connected as at 18 to a floating actuator lever 19 pivotally connected as at 20 to the upper end of a vertically reciprocating block or mounting 21 carried on a rod 22. The latter may be controlled by means of a suitable cam and is actuated to have a downward

movement when the lay is in its foremost position on detecting beats of the loom, and to have an upward movement when the shuttle is on the opposite side of the loom coincident with or subsequent to the movement of the pattern mechanism not shown. A stop pin 23 engages the right hand upper end of the floating lever as viewed in Fig. 1 to cause the link 16 to rise when the rod 22 is elevated.

10 A pivoted controller 24 is counter-weighted as at 25 so as normally to occupy the position shown in Fig. 1 out of the path of the right hand end of the lever 19. The latter is guided in a slotted upstanding finger 26 which may 15 be the means for supporting the stop pin 23.

The magazine frame is provided with a hub 30 having a relatively large stud 31 held therein against angular and longitudinal movements by a set screw 32. The transfer 20 ret mechanism designated generally at T has a hub 33 which pivots about the stud 31 but is normally held in raised position by means of a large coil spring 34. An adjusting nut 35 varies the torsional strain of spring 34.

25 A weft detector mechanism designated generally at D comprises a small stand 40 on which is mounted a feeler bed 41 and cap 42, these parts being held in position by a bolt 43 extending into the stand 40. A detector arm 30 44 extends rearwardly and has a roughened surface 45 to engage the yarn. A forwardly extending tail 46 is adapted to move to the left as viewed in Fig. 2 when indication of weft exhaustion is given by the feeler to rock 55 the controller 24 under the floating lever 19.

The parts heretofore described are substantially the same as those at present in use, the magazine part being set forth in United States patent to Ryon No. 1,030,748 and the 40 detector being substantially the same as that shown in United States patent to Payne No. 1,738,198.

As previously stated, it is an important object of my present invention to mount the 45 previously described link, floating lever, controller and detector mechanism so that they can move as a unit, and in carrying my invention into effect I provide a holding extension 50 on the stud 31 and mount thereon 50 the support 51 having the hub 52 through which the extension passes. A pair of set screws 53 determine the angular and longitudinal position of the support relatively to the extension 50. The lower part of the support 55 is provided with a slot 54 through which extends a bolt 55 the rear end of which passes through a vertical slot 56 formed in the stand 40. By means of the slots it is possible to position the detector mechanism correctly with respect to the controller and the floating lever.

The left hand end of the frame has an up-standing horn 57 in which is slidably mounted the previously described block or mounting 21. The part 26 which is slotted to receive

the lever 19 may be formed as an integral extension from the horn 57 and in a similar manner the pivot 58 for the controller may be mounted in fixed relation with respect to the horn 57.

It will be seen that the horizontal position of the pivot 20 and lever 19 in a direction parallel to the lay and also of the pivotal support for the controller 24 can be changed by varying the location of the hub 52 along the extension 50. The link 16 is mounted so that it can swing in a vertical plane parallel to the axis of stud 31 and it is for this reason that the parts mounted on the support 51 can be moved as described without objectionably disturbing the relation of the color slide with respect to the parts of the magazine with which it cooperates. During the assembling the detector will be in its correct position with respect to the controller and lever 19 and this relation can be maintained whenever it is necessary to move the detector in a direction parallel to the stud 31 to accommodate differing conditions in the shuttle.

From the foregoing it will be seen that I 90 have provided a simple support for the weft detector, controller, and actuator lever 19 requiring all these parts to move as a unit in a direction parallel to the lay. It will also be seen that the relation which these parts 95 sustain with respect to the magazine can be preserved by reason of the fact that the support 51 is mounted directly on an integral part of the magazine, that is, the stud 31. Furthermore, the support is movable about 100 stud 31 in a way to permit adjustment of the guide relatively to the mounting for the actuator lever.

Having thus described my invention it will 105 be seen that changes and modifications may be made therein by those skilled in the art without departing from the spirit and scope of the invention and I do not wish to be limited to the details herein disclosed, but what I claim is:

1. In a weft replenishing loom having a lay and a color slide, weft detecting mechanism, a controller to be moved by the latter, an actuator lever to be operatively related to the controller at weft exhaustion, connections 110 between the lever and the color slide, and a movable common support common to the detector, controller and actuator lever, said parts on the support being movable therewith as a unit in a direction lengthwise of the lay.

2. In a weft replenishing loom having a lay, a magazine, a weft detector, a controller movable by the detector, a magazine controlling actuator lever to be operatively related to the controller when the detector indicates weft exhaustion, and a common support mounted on the magazine and so related to the detector, controller and actuator lever 130

as to require said latter parts to move as a unit in a direction parallel to the lay.

3. In a weft replenishing loom having a lay, a magazine, a transerrer supporting member substantially parallel to the lay, a weft detector, a controller movable by the detector, a magazine controlling actuator lever to be operatively related to the controller when the detector indicates weft exhaustion, and a common support for the detector, controller and actuator lever requiring these parts to move as a unit in a direction parallel to the lay, said support being mounted on and capable of assuming a plurality of longitudinal positions with respect to the transerrer supporting member.

4. In a weft replenishing loom having a transerrer stud and a color slide movable in a direction transverse of the stud, weft detector mechanism, controller mechanism movable by the detector mechanism, actuator mechanism to be controlled by the controller, a link between the latter and the color slide movable in a plane parallel to the stud, and means to require said mechanisms to move as a unit in a direction parallel to the stud, the link moving to accommodate the movement of said mechanisms.

5. In a weft replenishing loom having a transerrer stud and a color slide movable in a direction transverse of the stud, detector mechanism, controller mechanism the position of which is determined by the detector mechanism, actuator mechanism the action of which is determined by the controller mechanism, a link between the latter and the color slide movable in a plane parallel to the stud, and means to require said mechanisms to move as a unit in a direction parallel to the stud, the link moving to accommodate the movement of said mechanisms, and said means being mounted on the stud.

6. In a weft replenishing loom having a lay, a support having an axis substantially parallel to the lay, an actuator lever, a reciprocating mounting for the lever movable in a direction transverse of said axis, and a guide for said mounting movable about the axis to assume any one of a plurality of angular positions with respect to the direction of reciprocation of the mounting.

7. In a weft replenishing loom having a lay, a supporting member extending substantially parallel to the lay, a weft detector mechanism, a controller mechanism, an actuator mechanism, and a support mounted on the member and movable therealong to assume any one of a plurality of longitudinal positions and normally fixed with respect thereto, the position of the controller and actuator mechanism with respect to the axis of the supporting member being fixed and the location of the detector mechanism being variable with respect to the support.

8. In a weft replenishing loom having a

lay, a reciprocating angularly movable color slide, an element operatively related to the color slide and movable independently of the latter in a plane substantially perpendicular to the longitudinal movement of the slide, an actuator for the element, a controller for the actuator, a weft detector to determine the position of the controller, and means to require the actuator, controller and weft detector to move as a unit in a direction parallel to the plane in which the element moves.

9. A supporting element for a magazine loom having a transerrer stud, an actuator lever, a controller and a weft detector, said support having provision for being secured in adjusted longitudinal position along the stud and having a pivotal support for the controller and having also a sliding guide for the actuator lever.

10. A supporting member for a loom having a transerrer stud, a weft detector, a controller and an actuator lever mounting, said member having provision for being supported in adjusted longitudinal position on the stud and having means to support the detector and the controller and having rigid therewith a guide for the actuator mounting.

In testimony whereof I have hereunto affixed my signature.
